COMBINED HOLDER AND MEASURING SPOONS

Bernhard Hasenstab, Akron, Ohio, assignor to Coventry Ware, Inc., Barberton, Ohio, a corporation of Ohio

Application July 19, 1951, Serial No. 15,964

Term of patent 7 years

(Cl. D44—29)

To all whom it may concern:

Be it known that I, Bernhard Hasenstab, a citizen of the United States, residing at Akron, State of Ohio, have invented a new, original, and ornamental Design for Combined Holder and Measuring Spoons, of which the following is a specification, reference being had to the accompanying drawings, forming a part thereof. In the drawings—

Fig. 1 is an exploded view of a combined holder and measuring spoons, showing my new design;

Fig. 2 is a plan view;

Fig. 3 is a view from the right side;

Fig. 4 is a front elevation;

Fig. 5 is a rear elevation; and
Fig. 6 is a bottom view.

I claim:

The ornamental design for a combined holder and measuring spoons, as shown.

BERNHARD HASENSTAB.
